MENDEL OSNOS, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

CIRCUIT ARRANGEMENT FOR WIRELESS SIGNALING.

Application filed February 12, 1923, Serial No. 618,667, and in Germany February 11, 1922.

In order to filter out the upper harmonics in the antenna waves of sending stations, special closed auxiliary circuits have, heretofore, been connected in the antenna circuit, and tuned to resonance with the operating frequency.

One of these prior arrangements for filtering out the higher harmonics consists of a trap circuit connected across the secondary 10 of the high frequency transformer used to couple the antenna to its high frequency energizing source. This trap circuit consists of a condenser and an inductance in parallel and the values of the capacity and inductance are so chosen that the circuit will resonate the frequency of the antenna circuit while the condenser will offer only a slight 15 resistance to the passage of the harmonic frequencies. The harmonic frequencies are thus by-passed from the antenna circuit, permitting the latter to be energized by substantially pure waves of its operating frequency. If there were no losses in the condenser and inductance of the trap circuit a 20 wattless current of the operating frequency would flow in it, whose presence would occasion no energy losses in the system. Theoretically, then, this arrangement would provide an efficient means for obtaining a pure 25 transmitter wave.

Another arrangement which has been used for this purpose consists of intermediate circuits coupled between the antenna and its high frequency energizing source.

These intermediate circuits are connected 30 to the antenna by coupling coils or air core transformers and, in view of the fact that the favorable coupling conditions are different for the operating waves and for the 35 waves of higher frequencies, the effect of the higher frequency waves or harmonics transversing the primary winding of the transformer, on the antenna circuit will be materially reduced as compared to the effect of 40 the operating waves.

However, the above described arrangements have also considerable drawbacks.

In the first-mentioned arrangement, the auxiliary circuit represents a source of 45 small but material losses because, due to its being tuned to resonance with the operating frequency, the auxiliary circuit is traversed by considerable currents of this frequency which cause correspondingly large

losses in the choke coil and can no more be 55 considered as wattless currents.

On the other hand, in the second named arrangement, the reaction of the higher frequency waves on the antenna circuit, although reduced, is not entirely eliminated 60 because the primary winding of the coupling air core transformer is traversed by the higher frequency waves.

In accordance with the present invention, the above-mentioned drawbacks are eliminated by using a combination of the two systems in which an intermediate circuit is used 65 for coupling the source of energy to the antenna and in which the primary of the air core transformer, coupling the source to the 70 antenna, is shunted by a condenser serving to form a tuned circuit and to by-pass the higher frequencies.

The invention may be more clearly understood from the following description which 75 should be read in connection with the accompanying drawing, in which the single figure shows a diagrammatic circuit arrangement conforming to the invention.

Referring to the figure, a generator *g* 80 serves to energize an antenna *A*, the generator being coupled to an intermediate circuit by means of the transformer *t*, a condenser *c* being interposed in the generator circuit for tuning. The intermediate circuit includes the secondary of the transformer *t* in series with a tuned circuit comprising an inductance *l* shunted by a condenser *k*, this latter circuit being tuned to resonate the 85 operating frequency. The antenna circuit is coupled to the intermediate circuit by coil *l*, in inductive relationship with the inductance *l*. With this arrangement the advantages of both the former systems are obtained without the disadvantages of either. The intermediate circuit serves to prevent short circuits and owing to the different coupling conditions for the operating waves and the higher frequencies, the effect of the latter 90 on the antenna are materially reduced. The condenser *k* further decreases the effects of the higher frequencies on the antenna as it 95 serves as a by-pass for them. The resonant circuit *k*—*l* is not a source of appreciable losses because the heavy currents circulating therein at the operating frequency are used for energizing the antenna circuit. This, moreover, avoids the necessity of providing

100
105

a special air core transformer for coupling to the antenna circuit.

It will be obvious that the invention is adapted to other modifications, which will readily occur to those skilled in the art; for example, only a part of the inductances l and l_1 may be used for coupling to the antenna circuit. The showing, therefore, should be taken in exemplary and not in a limiting sense, as I intend to be limited only as indicated by the scope of the following claims.

Having described my invention, what I claim is:

1. An arrangement for high frequency signaling comprising a source of high frequency energy, an oscillatory circuit coupled thereto comprising an inductance having a condenser connected directly across

its terminals and a transmitting circuit coupled to said inductance, said inductance and capacity being so adjusted that the oscillatory circuit will resonate the transmitted frequency and the condenser will by-pass substantially all the undesirable higher frequencies. 20

2. An arrangement for high frequency signaling comprising a source of high frequency energy, an oscillatory circuit coupled thereto consisting of a condenser and inductance in parallel and a transmitting circuit coupled to said inductance, said inductance and capacity being so adjusted that the said oscillatory circuit will resonate the transmitting frequency and the condenser will by-pass substantially all the undesirable higher frequencies. 25 30 35
